UNITED STATES PATENT OFFICE

ROYAL DOUGLASS, OF SOUTH BELLINGHAM, WASHINGTON

AUTOMATIC COOLER OR CAN-TRAY UNLOADER

Application filed March 28, 1929; Serial No. 350,606.

This invention relates to an automatic cooler or can tray unloader.

The primary object of the invention is to provide a novel apparatus for unloading cooler or can trays to facilitate the unloading of such coolers or trays, and the feeding of filled cans into boxes or cases for shipment. Through the employment of this machine, about 600 cases of 48 cans of canned products can be put in boxes per hour, saving a great deal of labor. The old method involved manual labor which was slow and tedious; but with the present machine, the labor can be reduced from 50 to 75%, at the same time increasing the production per hour.

Another object of the invention is to provide a machine of this character, including an elevating truck or carriage designed to receive, one at a time, the coolers or can trays, and combined with means for automatically elevating the truck after it has been loaded, and for conveying the truck on to a runway.

A further object is to combine in such a machine, an invertible carriage with the elevating truck, the carriage being designed to take the cooler or can tray from the truck, to invert the same and deposit it on an endless conveyor from which the cans are transferred to the box loading devices.

A still further object is to provide a machine of this type, including various movable elements which are semi-automatic in their action, and under the control of the operator.

With the foregoing objects outlined and with other objects in view which will appear as the description proceeds, my invention consists in the novel features hereinafter described in detail, illustrated in the accompanying drawings, and more particularly pointed out in the appended claims.

Referring to the drawings,

Fig. 1 is a side view of my apparatus.

Fig. 2 is a plan view with the elevating truck and invertible carriage removed.

Fig. 3 is an enlarged transverse sectional view on the line 3—3 of Fig. 1.

Fig. 4 is an end view with parts removed.

Fig. 5 is a section on the line 5—5 of Fig.

2, showing the invertible carriage and truck on the supporting frame.

Fig. 6 is a section on the line 6—6 of Fig. 2.

Fig. 7 is a bottom plan view of the elevating truck.

Fig. 8 is a side view of the same.

Fig. 9 is an end view of the truck.

Fig. 10 is a top plan view of the invertible carriage.

Fig. 11 is a side elevation of the same.

Fig. 12 is an end view of said carriage.

Figs. 13, 14 and 15 are detail sectional views of the same.

Figs. 16 and 17 and 18 are detail views of the elevating truck.

Fig. 19 is an enlarged view of the elevating truck track, showing elevating truck in dotted lines.

Fig. 20 is an enlarged sectional view of the truck track, taken on the line 20—20 of Fig. 19.

Figs. 21 and 22 are plan views of parts of the truck track.

Fig. 23 is a plan view of part of the invertible carriage truck.

Figs. 24 and 25 are plan views of parts of the truck track.

Figs. 26 and 27 are views of a portion of the inclined extension track.

In the drawings, 1 designates a wheel supported frame provided below its top with tracks 2 on which the elevating truck travels. These tracks are detachably connected to inclined track extensions 3 that are mounted on supporting standards 4.

The elevating truck 5 is designed to roll along the tracks and their extensions, and when the truck is in starting position, it rests at the lower ends of the track extensions, and abuts against the stop bar 6 which is mounted on the end standard 4.

The details of the elevating truck are best shown in Figs. 7, 8, 9, 16 and 17, and it will be noted from these figures, that the truck includes a platform 7, provided at one end with an angle bar 8, that functions as a gauge for squaring the cooler or can tray on the truck.

Shafts 9 are located on the under side of the platform, and journaled in bearings 10.

that are secured to the platform, and each shaft preferably consists of two sections detachably connected by a coupling 11, which permits the sections to be readily detached 5 from the platform.

Each shaft is provided at its ends with eccentric stub shafts or axles 12, on which the supporting wheels 13 are journaled. These wheels roll along the tracks 2 and their extensions 3. Due to the eccentric arrangement of the axles 12, it is obvious that when the shafts 9 are turned in their bearings 10, the wheels 13 will move in arcs having the axes of the shafts 9 as their centers, and this 10 movement is utilized for raising and lowering the platform 7.

In order that the shafts will swing in unison, they are connected by a link 14 which is pivotally connected to arms 15, fast on the 20 shafts 9.

Actuating arms 16, 16a for the shafts are fixed to the same, intermediate their ends, and stop arms 17, 17a are fast on the shafts and engageable with the platform to limit 25 the swinging movement of the shafts. The arms 16, 16a are connected to the hauling cables in a manner hereinafter described.

Brackets 18, depend from the ends of the platform, and support pulleys 19, 19a. Each 30 bracket preferably has a keeper 20 to prevent the cable from riding off the pulley.

By referring now to Figs. 1, 2, 7, 8 and 9, it will be observed that one of the cables 21, heretofore mentioned, has one of its ends connected to a winding drum 22, mounted in the frame 1, and from this drum, the cable passes over a sheave 23, positioned on one of the cross bars 24 of the frame. From this sheave, the cable extends forwardly and engages the 40 pulley 19a, from which it extends, and has its other end connected to the actuating arm 16. It will therefore be seen (Fig. 5) that when the winding drum is actuated, the cable will pull on the arm 16 and cause the shafts 45 9 to turn about 160 degrees, until the arm 17 contacts with the under side of the platform 7. Due to this movement, the platform will be elevated, and as soon as the stop arm 17 contacts with the platform, the elevating truck will be pulled upwardly by the 50 cable on the track extensions, and finally on to the tracks 2. As the truck travels along the tracks, one of its front wheels will strike a pivoted detent 25 (Figs. 3, 19, and 20), which by means of a cord 25a passing over guide pulleys 25b, 25c, will function to throw the clutch of the winding drum, and thus release the clutch from driving engagement with its motor 26. The winding drum will 55 thus come to rest, but the truck will continue to move, due to momentum, and will be finally halted by stop arms 27 on the truck contacting with similar stop arms 28a on the frame 1.

When the truck has reached this position,

it will be proper location to allow the invertible carriage to take the cooler or can tray with the cans contained therein, off the truck. In order that this operation may be clearly understood, I will now describe the invertible carriage. As best shown in Figs. 8 to 10 inclusive, this carriage 28 also includes a platform 29, provided intermediate its ends with a cross bar 30, fixed to the platform by any suitable means, and provided at its ends with arms 31 which project at angles to the bar and platform. Stud shafts 32 are fixed to these extensions, and provided with anti-friction rollers 33 that travel on tracks 34 mounted on the frame at a higher elevation than the tracks 1. In addition, to the anti-friction roller, each shaft 32 carries a guide disk 35, and the guide disks of the two shafts bear against opposite sides of the frame 1 for maintaining the carriage in proper alignment.

Each disk has a pair of projecting cams 36 for actuating movable stops 37 which will be further referred to hereinafter.

Hand wheels 38 are fast on the outer ends of the stationary shafts 32, and these wheels are employed by the operator or operators to swing the platform approximately 180 degrees, using the axes of the shafts 32 as a center.

Other rollers 39 travel on one of the edges of the tracks 34, and are combined with guide disks 40 which engage the inner surfaces of the tracks 34, and also function to maintain the platform 28 in proper alignment.

Each disk 40 and its associated roller 39 is mounted on an axle 41, carried by a bracket 42 fixed to the platform, near one end of the same.

The invertible carriage is completed by a pair of lifting arms or extensions 43, which project from posts 44, fixed to one end of the platform, and these extensions are braced by brackets 45.

At this point it will be noted that the width of the truck platform 7 is somewhat less than the distance between the arms 43 of the invertible carriage, in order that said arms may be moved with the invertible carriage along the sides of the truck platform, with a view of permitting the cooler or can tray to come to rest on the arms 43, when the invertible carriage 28 is in inverted position, and the platform of the lifting truck is lowered.

Heretofore in the description, I have brought the lifting truck with its load into its halted position on the tracks 1. With the truck and its load in this position, and the carriage inverted, it will be obvious that when the hand wheels 38 are pulled in the proper direction, the carriage will roll along the tracks 34 until the carriage assumes a position directly above the truck. When in this position, the lifting arms 43 will lie directly

below the lateral edge portions of the cooler or can tray, and at this time, the platform of the truck is lowered so as to relieve the truck of the load, and place this burden on the carriage. For the purpose of lowering the platform of the truck, and then transferring the truck back to its initial position at the lower end of the inclined extensions of the track, another cable 45 is employed. This cable has one of its ends connected to a winding drum 47 that is also driven by the motor, through the medium of a clutch. This cable extends from the winding drum about a sheave 48 mounted on the standard of the track extension, and from this sheave, the cable extends over the pulley 19 on the truck, and has its other end fixed to the actuating arm 16a of the truck. Consequently, when this winding drum is actuated, the cable will first pull on the arm 16a and swing the shafts 9 until the stop arm 17a contacts with the platform 7, and then, as the cable continues to wind, the truck will be pulled first along the tracks 1, and then down the inclined extensions, until it comes to rest at the lower end of the track extensions.

At this time, the loaded cooler or can tray is supported by the carriage 28, and it may be mentioned that the operator, in swinging the carriage back to its initial position, will cause the cams 36 to depress the stops 38, so that these stops will not interfere with the movement of the carriage along its tracks. Each of these stops preferably consists of a spring pressed rod connected by a link 50 to a part of the main frame. These links are in the path of movement of the disks 35, and consequently, when either link is engaged by one of the cams 36, the stop connected to that link will be depressed, and this will permit the rollers 33 to pass along their tracks without interference by the stops, when such interference is not desired. On the other hand, the stops perform their required function when necessary.

While the carriage is being inverted, one end of the cooler or tray will come to rest against the post 44 of the carriage, and these posts will prevent the load from falling off the carriage while the latter is being inverted. After reversal of the carriage, the movement of the hand wheels is continued to feed the load toward the discharge end of the machine, and in such movement, the rollers 39 travel along their tracks until they reach the ends of the same, and as these ends terminate short of the discharge end of the machine, it is obvious that as soon as the rollers 39 drop off the ends of their tracks, the carriage will assume an inclined position, and the forward edge of its platform will come to rest clearing endless belt 51. At this time, and while the carriage remains in an inclined position, it may be moved back toward the center of the frame, so that the cool-

er or can tray will slide off and be deposited on the endless belt. At this time, the endless belt is in motion, and the operator may shift the cooler around to bring the cans into proper alignment on the belt, and then the cooler or tray may be lifted off, leaving the cans on the belt. Now the belt is in motion for the purpose of feeding the cans into lateral runways 53, arranged at the discharge end of the machine, and these runways communicate with oppositely extending tracks 54, which may lead to boxing machines, not shown.

The endless belt is preferably mounted on rollers 55, journaled in suitable bearings on the frame, and one of these rollers is provided with a sprocket wheel which is driven by suitable sprocket wheels and chains 57, from the motor. Of course, any suitable clutch, (not shown) is used in this transmitting mechanism, in order that the endless belt may be halted while the motor continues to revolve.

I prefer to mount the main frame of the machine on wheels, in order that it can be moved easily from one place to another, and as the inclined extensions 3 of the elevating truck tracks are detachably connected, this will also facilitate the shifting of the machine from place to place.

From the foregoing description, it is obvious that I have provided a machine involving an elevating truck which may receive loaded can trays, one after the other, and elevate the same into a position where they may be readily handled by an invertible carriage, the latter being actuated by the operator or operators for transferring a loaded tray on to an endless belt, from which the cans may be expeditiously fed into machines to be packed into their boxes or shipping containers, in the shortest time possible, and with a minimum expenditure of labor. It will be manifest to those skilled in the art that various changes may be made in the details disclosed without departing from the spirit of the invention as expressed in the claims.

What I claim and desire to secure by Letters Patent is:

1. A can tray unloader, including a track, an elevating truck mounted on the track and having a platform to receive a loaded can tray, and means including hauling flexible elements for elevating said platform and moving the truck along the tracks.

2. In a machine of the character described, a track, a truck mounted on the track and having an elevatable platform, and means including hauling flexible elements for elevating the platform and for moving the truck along said track.

3. In a machine of the character described, a track having a downwardly inclined extension, a truck movable along the track and having an elevatable platform, and means in-

- cluding hauling flexible elements for elevating the platform relatively to the track and for moving the truck along the track.
4. In a machine of the character described, a track, rollers on the track, shafts having eccentric portions on which the rollers are journaled, a platform, bearings for the shafts connected to the platform, and means including hauling flexible elements for rotating the shafts in their bearings, and thereby raising said platform, and for moving the platform, shafts and wheels along said track.
5. In a machine of the character described, a track, wheels mounted on the track, rock shafts having eccentric portions on which the wheels are journaled, a platform, bearings for the shafts supporting said platform, connecting means between the shafts to permit the same to be rocked in unison, motor actuated means and means connected to the motor actuated means for rocking said shafts and moving the wheels, shafts and platform along said track.
6. In a machine of the character described, a track, a wheel supported truck mounted on the track and having an elevatable platform, a winding drum mounted adjacent to the track, means for elevating said platform, and a flexible element connecting the last mentioned means to the drum, whereby when the drum is rotated, the flexible element will first raise the platform, and afterwards move the truck along the track.
7. In a machine of the character described, a track, a truck movable along the track and including a platform, shafts supporting the platform, and rollers mounted on the shafts, the portions of the shafts on which the rollers are mounted being arranged eccentrically to the remainder of the shafts, whereby, when the shafts are rocked, the platform will be elevated, stops on the shafts engageable with the platform for limiting the upward and downward movement of the platform, and means for rocking said shafts and moving the truck along the track.
8. In a machine of the character described, a track, an elevating truck movable along the track and having an upwardly and downwardly movable platform, means for elevating the platform and for moving the truck along the track, said means including a motor, a winding drum, a clutch interposed between the motor and winding drum, a flexible element connecting the drum and truck, and means actuated by the truck as it moves along the track for shifting the clutch to disengage the winding drum from the motor.
9. In a machine of the character described, a track, a truck movable along the track and having an upwardly and downwardly movable platform, and means for shifting said platform and for moving the truck along the track, said means including a motor, an actuating member, a clutch interposed between the motor and actuating member, and means operated by the truck as it moves along the track for shifting said clutch.
10. In a machine of the character described, a pair of tracks, one track being at a higher elevation than the other, an elevatable truck mounted on one of said tracks, means for elevating the truck and for moving the same along its track into a position adjacent to the other track, and an invertible carriage mounted on one of said tracks and adapted to take a load from the elevatable truck and to invert said load.
11. In a machine of the character described, upper and lower tracks, an elevatable truck mounted on the lower track, means for elevating and lowering said truck and for shifting the same along the lower track, portions of said tracks overlapping, and an invertible carriage mounted on the upper track and arranged to relieve the elevatable truck of a load and to invert said load.
12. In a machine of the character described, upper and lower tracks, the lower track having a downwardly and outwardly inclined extension, an elevatable truck mounted on the lower track, means for elevating and lowering the truck and for shifting the latter along the lower track, portions of said tracks overlapping, and an invertible carriage mounted on the upper track and adapted to be moved into a position over the truck when the latter is in a certain location, and to relieve the truck of its load when said truck is lowered.
13. In a machine of the character described, upper and lower tracks, the lower track having a downwardly and outwardly extending portion, a truck mounted on the lower track and having an upwardly and downwardly movable platform, means for raising and lowering said platform and for shifting the truck along the lower track, an invertible carriage mounted on the upper track and adapted to receive a load from the truck, means for use in inverting said carriage, and a conveyor arranged to receive a load discharged by the carriage.
14. In a machine of the character described, a track, means for feeding a load into a position adjacent said track, and an invertible carriage mounted on the track and adapted to receive the load, said carriage including a platform, main supporting wheels for the platform arranged at the medial portion of the latter and functioning as fulcrums to permit the platform to be turned over, and balancing wheels mounted on the platform and arranged near one end of the same.
15. In a machine of the character described, a track, means for conveying a load into a position adjacent said track, and an invertible carriage mounted on the track and adapted to receive the load and to invert the same, said carriage including a platform,

main supporting wheels for the carriage located at the medial portion of the same and functioning as fulcrums when the carriage is inverted, other supporting wheels for the carriage mounted near one end of the platform, and a hand wheel having its axis in alignment with the axes of the main supporting wheels, and fixed to the platform to permit the operator to invert the latter.

16. In a machine of the character described, a track, means for conveying a load into a position adjacent to the track, and an invertible carriage adapted to receive the load and mounted on said track, said carriage including a platform, ears fixed to the platform and positioned at the medial portion of the same, laterally projecting shafts fixed to said ears, main supporting wheels rotatably mounted on said shafts and engageable with said track, balancing wheels mounted on the platform adjacent one end of the latter, and a hand wheel fixed to one of said shafts, whereby the operator may invert the carriage while moving the same along said track.

17. In a machine of the character described, a track means for feeding a load into a position adjacent to said track, and an invertible carriage mounted on the track and adapted to receive the load from said means, said carriage including a platform, supports projecting laterally from the medial portion of said platform, projecting shafts fixed to said supports, supporting wheels rotatably mounted on the shafts and engaging said track, means for balancing said platform, means for guiding the platform against lateral movement, and means for use in moving the platform along the track and for inverting the latter.

18. In a machine of the character described, a track means for feeding a load into a position adjacent to said track, an invertible carriage mounted on the track and adapted to receive the load from said means and invert the load, movable stops obstructing the track, and means on the carriage for shifting the stops out of the positions in which they obstruct the carriage.

19. In a machine of the character described, a track, means for feeding a load into a position adjacent to said track, and an invertible carriage mounted on said track and adapted to receive and invert the load, said carriage including a platform and arms extending along one face of the platform in spaced relation to the latter.

20. In a machine of the character described, tracks, a truck movable along one of said tracks and having a platform to support a load, and an invertible carriage mounted on the other track and adapted to take the load from the truck and invert the load, said carriage being provided near its side edges with load receiving arms spaced apart a greater

distance than the width of the truck platform.

21. In a machine of the character described, a wheel supported frame, upper and lower tracks mounted on the frame, a downwardly and outwardly inclined extension for the lower track, a truck mounted on the lower track and having an upwardly and downwardly movable platform, means for shifting the platform and for moving the truck along its track, said truck being adapted to convey a load, an invertible carriage mounted on the upper track and adapted to receive the load from the truck when the platform is lowered, means for use in inverting said carriage, and a conveyor mounted on the frame and arranged to receive the load from the invertible carriage.

In testimony whereof, I have signed this specification.
